UNITED STATES PATENT OFFICE.

DONALD C. DAVIS, OF DEPEW, NEW YORK, ASSIGNEE TO GOULD COUPLER COMPANY,
OF NEW YORK, N. Y.

CAR JOURNAL-BOX.

1,109,281.

Specification of Letters Patent.

Patented Sept. 1, 1914.

Application filed November 13, 1913. Serial No. 501,119.

To all whom it may concern:

Be it known that I, DONALD C. DAVIS, a citizen of the United States, residing at Depew, in the county of Erie and State of New York, have invented a new and useful Improvement in Car Journal-Boxes, of which the following is a specification.

This invention relates to railway car journal boxes of the kind having a filling opening at the outer end which is closed by a lid or cover hinged at its upper end to the upper part of the box. The lid is ordinarily provided with a spring device which holds it in closed position and which is compressed or strained in opening the lid and yieldingly resists the upward or opening movement of the lid. The journal box lid known as the Master Car Builders' lid is hinged to an upwardly projecting lug on the top of the journal box by a hinge-pin or bolt which passes through the box lug and through lugs on the lid which are located at opposite sides of the box lug. This lid is held closed by a leaf spring which is secured on the inner side of the lid and bears at its free end against the hinge lug on the journal box.

One object of this invention is to provide a boltless or pinless hinge connection for the journal box lid which is of simple, strong and inexpensive construction, which permits the lid to be readily attached to and detached from the box, but prevents the accidental detachment of the lid, and which is of such construction that in the event of the lid being broken or lost, the ordinary Master Car Builders' lid can be substituted therefor and hinged to the box by a hinge-pin or bolt in the usual manner.

Another object of the invention is to provide a spring closing device for the lid which acts to maintain the connection between the parts of the lid hinge and prevent the accidental detachment of the lid, but which enables the lid to be detached when desired with the minimum labor and which does not in anywise interfere with the use of a Master Car Builders' lid on the journal box.

In the accompanying drawings: Figure 1 is a front or end elevation of a railway car journal box embodying the invention, a portion of the lid being broken away to disclose the underlying parts. Fig. 2 is a fragmentary longitudinal sectional elevation thereof in line 2--2, Fig. 1. Fig. 3 is a fragmentary longitudinal sectional elevation thereof

showing the lid raised. Fig. 4 is a fragmentary front end elevation showing the hinge lug on the journal box. Fig. 5 is a fragmentary plan view, partly in section, in line 5--5, Fig. 2. Fig. 6 is a sectional elevation in line 6--6, Fig. 5. Fig. 7 is a similar view showing the position to which the lid is moved for connecting it with and disconnecting it from the box.

Like reference characters refer to like parts in the several figures.

A represents a railway car journal box, and B a lid which closes the usual filling opening at the outer end of the box. With the exception of the hinge connection between the lid and the journal box and the spring device for closing the lid, the journal box and the lid may be of any usual or suitable construction.

The journal box is provided above the filling opening with a hinge lug C which rises from the top of the box between the sides thereof. This lug is provided at its opposing sides with integral lateral bosses or journals c which are of mutilated cylindrical shape, preferably having upper and lower segmental cylindrical bearing faces c' and flat front and rear faces c'', see Fig. 6. The lid is provided at its upper portion with a hood or chambered part D which is adapted to extend over and partially inclose the hinge lug C. This hood is provided at its opposite sides with hollow cylindrical bosses or lateral extensions E adapted to receive the journals c of the lug C and to turn thereon when the lid is opened or closed. The cylindrical walls of the bosses E are provided at their lower sides with slots e which are of a width to permit the bosses to pass through the slots when the lid is opened to a position to bring the slots opposite to the narrowest portions of the journals as indicated in Fig. 7. When the lid has been put in place on the hinge lug C by slipping the bosses E downwardly over the journals c of the lug C, the lid can be turned or swung on the journals c to open and close the lid.

In the opening and closing movements of the lid the bosses E bear and turn on the upper and lower segmental cylindrical faces e of the journals. When the lid is in any position, except a partially opened position about as indicated in Fig. 7, the journals c will overhang the cylindrical walls of the lid bosses E at one side or the other of the

entrance slots *e*, and will thus prevent the lid from being lifted off of the journals. Fig. 6 shows how the journals and bosses interlock when the lid is in the closed position. The lid, therefore, cannot be detached from the box, except by first turning it to the predetermined detaching position and, as hereinafter explained, the closing spring for the lid is strained to its maximum extent when the lid is in this detaching position and thus serves to prevent the possibility of the lid being accidentally detached.

F represents a spring for holding the journal box lid in its closed and raised or opened positions and for yieldingly resisting the opening of the lid. A coil spring is shown for this purpose which surrounds a guide rod *G* which is hinged at its upper end to the journal box adjacent to the hinge lug *C* and is adapted to slide in a hole in an abutment *g* which projects inwardly from the lid. The spring bears at one end against an enlargement or crosshead *g'* of the rod *G* and at its other end against the abutment *g* on the lid. This abutment is preferably rounded or convexed at the point where the spring bears thereon to prevent binding and cramping the spring when opening and closing the lid. The rod *G* may be pivoted at its upper end to the box in any suitable way. As shown the cross head *g'* at the upper end of the rod is located between ears *h* projecting forwardly from the hinge lug *C* and is pivoted thereto by a pin or rivet *h'* passing through holes in said cross head and ears. The pivot pin *h'* is accessible and can be inserted or removed when the lid is in the open position shown in Fig. 3, thus permitting the connection of the spring device to and 40 its disconnection from the box. The arrangement of the spring and the position of the pivot for the spring rod *G* with reference to the axis of the hinge for the lid are such that the compression of the spring *F* is increased by opening the lid and is at its maximum when the lid has been opened substantially to the position indicated in Fig. 7 in which the lid is adapted to be lifted off of the hinge lug. The spring thus acts to 50 hold the lid firmly down on the hinge lug and prevents the accidental detachment of the lid from the box.

The hinge lug *C* in the construction shown is recessed at its rear side at *i* for the purpose of eliminating useless weight in the journal box, but the recessing of the lug is in nowise essential to the invention. This lug *C* is preferably made of the same length crosswise of the box as the hinge lugs on the Master Car Builders' journal boxes and is provided with a hole *K* for a hinge-pin or bolt, thus enabling a Master Car Builders' journal box lid to be placed on the journal box and hinged thereto by the usual bolt or box and hinged thereto by the usual bolt or pin passing through the hole *K*. The lug

C is also provided at its outer or front side with a bearing face *l* for the upper end of the flat spring ordinarily employed on the Master Car Builders' journal box lid. The ears *h* to which the spring rod is pivoted are spaced apart far enough to permit the spring of the Master Car Builders' lid to extend between them and bear against the face *l* of the hinge lug *C*. The construction described thus does not in any wise interfere with the substitution of a Master Car Builders' lid on the journal box in place of the lid *B*. The spring *F* and spring rod *G* are, of course, removed when a Master Car Builders' lid is to be used on the box.

I claim as my invention:

1. The combination with a journal box, and a lid therefor, of a boltless hinge for said lid comprising a lug on the box provided with laterally projecting journals and having a hole extending axially through said lug and said journals, and hollow bosses on said lid which receive and are adapted to turn on said journals, said lid being adapted to be opened and closed by a simple swinging movement about said journals, said bosses having slots through which said journals are adapted to pass when said lid is swung to a predetermined position, substantially as set forth.

2. The combination with a journal box, and a lid therefor, of a boltless hinge for said lid comprising a lug on the box provided with laterally projecting journals, and hollow cylindrical bosses in said lid which receive and are adapted to turn on said journals, said lid being adapted to be opened and closed by a simple swinging movement on said journals, said bosses having slots in the lower portions of their cylindrical walls, through which said journals are adapted to pass when said lid is swung to a predetermined position, substantially as set forth.

3. The combination with a journal box, and a lid therefor, of a boltless hinge for said lid comprising a lug on the box provided with laterally projecting mutilated cylindrical journals and hollow cylindrical bosses on said lid which receive and are adapted to turn on said journals, said bosses having slots in their cylindrical walls through which said journals are adapted to pass only when said lid is swung to a position in which said slots are opposite the narrowest parts of said journals, substantially as set forth.

4. The combination with a journal box, and a lid therefor, of a boltless hinge for said lid comprising a fixed part on said lid which is adapted to turn on a fixed part on said box, said parts having interlocking portions which prevent the disconnection of said parts except when said lid is in a predetermined position, and a closing spring for said lid which acts to hold said parts in

connection, and which exerts its maximum force when said lid is in position for disconnection from said box, substantially as set forth.

5. The combination with a journal box, and a lid therefor, of a boltless hinge for said lid comprising a lug on the box provided with an axial hinge pin hole and with laterally projecting journals concentric with said hole, and hollow bosses on said lid which receive and are adapted to turn on said journals, said lid being adapted to be

opened and closed by a simple swinging movement about said journals, said bosses having slots through which said journals are adapted to pass when said lid is swung to a predetermined position, substantially as set forth.

Witness my hand, this 28th day of October, 1913.

DONALD C. DAVIS.
